(57) **CLAIM**

I claim the ornamental design for a stand for a computer, as shown and described.

DESCRIPTION

FIG. 1 is a left front perspective view of a stand for a computer.

FIG. 2 is a top plan view thereof.

FIG. 3 is a left side elevation view thereof, where the right side elevation view is identical to the left side elevation view.

FIG. 4 is a bottom plan view thereof.

FIG. 5 is a front elevation view thereof; and,

FIG. 6 is a back elevation view thereof.
